Filed Aug. 20, 1962, Ser. No. 71,369

Term of patent 14 years

(Cl. D14—27)

FIG. 1

FIG. 2

FIG. 3

FIG. 4

FIGURE 1 is a side elevation of an automobile showing my new design.

FIGURE 2 is a rear view thereof.

FIGURE 3 is a front view thereof.

FIGURE 4 is a top view thereof.

The dominant features of my design reside in the portions shown in full lines, said features being characterized by the circular convex roof disposed at a downward angle from front to rear and having diagonal lines forming a pattern of multiple diamonds, the lines being of a color contrasting with that of the surface of the roof and applied over said surface, together with a crescent shaped spot-light on the forward end of the roof.

I claim:

The ornamental design for an automobile, substantially as shown and described.
